UNITED STATES PATENT OFFICE.

ADELBERT E. BRONSON, OF CLEVELAND, OHIO.

VALVE FOR PNEUMATIC TIRES.

1,426,350.

Specification of Letters Patent. Patented Aug. 22, 1922.

Application filed June 20, 1918. Serial No. 241,011.

To all whom it may concern:

Be it known that I, ADELBERT E. BRONSON, a citizen of the United States, residing at Cleveland, in the county of Cuyahoga, State 5 of Ohio, have invented certain new and useful Improvements in Valves for Pneumatic Tires, of which the following is a specification.

The object of this invention is to improve 10 the construction of valves now in use in pneumatic tires, and is designed practically as an improvement on the construction shown in the patent to Greenwald No. 1,255,411, dated February 5th, 1918. The 15 objects are to make a compact and serviceable valve which shall be a satisfactory manufacturing proposition and shall not be liable to injury. These and other objects will appear as the description proceeds:

20 In the drawings:

Fig. 1 is a cross-section through the assembled valve.

Fig. 2 is a view of the valve stem detached.

Fig. 3 is a plan view of the valve "insides".

25 This invention relates to the mechanism known as the valve "insides", which is designed to be placed in the well known valve stem shown at 1 having a reduced outer end or nipple 2, the inside of which is screw threaded as at 3 for the reception of the insides. Below the nipple the inside of the 30 valve is provided with an inclined shoulder 4 communicating with a bore 5 leading through the stem.

35 The removable part of the valve or the "insides" comprises a barrel 6 screw threaded on its outer side to fit the threads 3 on the inside of the nipple, the upper end of the barrel being bent at right angles to the 40 main portion to form a flange 7 the central part of which is provided with an opening 8 through which air may pass into and out of the tire. From the opening 8 are formed diametrically positioned recesses 9. The 45 lower part of the barrel is extended a short distance to form a sleeve 10. Into the lower end of the barrel is adapted to be placed a plug or tube 11, the upper end of which contacts with a shoulder 12 on the inside of 50 the barrel. Near the middle of the tube, but preferably above the midway point, there is formed a groove 13 having a right angled shoulder 14 in which is placed a gasket 15 of rubber or other suitable material adapted 55 to be forced into intimate sealing contact

with the shoulder 4 on screwing in of the barrel 6. The lower end of the sleeve 10 extends just over the entrance to the groove and is spun or pressed down into the groove to lock the two parts in position and serving 60 also to hold the packing 15 in place. The tube is a tight fit in the barrel and the spun down edge of the sleeve in the barrel makes a firm non-rotative connection between these two parts of the inside. At about the 65 beginning of the groove there is formed on the inside of the tube a shoulder 16 serving as one of the seats for the spring to be described, the bore 17 of the tube being accordingly reduced. The upper end of the 70 tube is thus recessed to receive the lower portion of the spring, the upper portion of the spring being received in the barrel. The lower end of the tube is brought to a thin edge as at 18 to form a seat for the valve. 75 By positioning the gasket about midway of the tube it is possible to bring the valve members down into the tube and away from the shoulder and gasket where there will be a freer circulation for the air into and out of the valve mechanism. The body of the tube below the gasket is thick and stout and not liable to injury.

The valve stem or post is shown at 19 and compromises a central portion adapted 80 to pass through the tube, the upper end being enlarged as shown at 20 to form a guide for the spring and surmounted by an enlargement 21 forming a spring abutment from which extends a flattened end 22 85 which, when the valve is assembled, passes through the opening 8 and is received in the recesses 9 whereby it may be used for rotating the barrel into and out of the nipple. The upper end of the stem is preferably 90 elongated to extend slightly above the top of the nipple. A light coil spring 23 surrounds the upper end of the stem being seated between the shoulder 16 and the abutment 21 and serving to hold the valve stem at the 95 upper limit of its movement.

On the lower end of the valve stem is formed a shoulder 24 and below the shoulder is seated the cup-like valve 25 in the upper end which is placed a small ring gasket 26 105 which is held in contact with the lower edge 18 of the tube by the spring, the shoulder 24 acting as a stop for the valve.

When the parts have all been assembled 110 in the position shown in Fig. 1, the lower-

most end of the valve stem is pinched, as at 27 directly below the valve and they are thus held together.

It is obvious that changes and modifications may be made without departing from the spirit of the invention or sacrificing any of its benefits, and the details shown herein are susceptible of alteration without changing the scope of the invention.

10 I claim:

1. In a valve construction for pneumatic tires, the combination of a valve stem having an internally screw-threaded nipple and a shoulder below the nipple, a barrel having screw threaded engagement with the nipple, the interior of the barrel being provided with a shoulder, a tube, the upper end of which is received in the barrel against the shoulder, a groove in the exterior of the tube 15 at the lower edge of the barrel, the edge of the barrel being bent within the groove and co-operating with an end wall of the
- 20

groove, a gasket bearing against the shoulder on the valve stem, and valve mechanism located within the barrel and the tube and 25 adapted to close the lower end of the tube.

2. In valve construction for pneumatic tires, the combination of a valve stem having an internally screw-threaded nipple and a shoulder below the nipple, a barrel having a screw-threaded engagement with the nipple, the interior of the barrel being provided with a shoulder, a tube, the upper end of which is received in the barrel against the shoulder, a groove in the exterior of the tube 30 at the lower edge of the barrel, the edge of the barrel being bent within the groove, and co-operating with an end wall of the groove a gasket bearing against the shoulder on the valve stem, a valve post traversing the barrel and the tube, a spring within said parts and a valve on said post closing the lower end of said tube.

ADELBERT E. BRONSON.
